UNITED STATES PATENT OFFICE

146,989

DESIGN FOR A HAIR CUTTING COMB

Sanford E. A. Sanders, Los Angeles, Calif., assignor to Sta-Neet Corporation, a corporation of California

Application June 8, 1946, Serial No. 130,561

Term of patent 14 years

(Cl. D86—8)

To all whom it may concern:

Be it known that I, Sanford E. A. Sanders, citizen of the United States, residing in the city of Los Angeles, in the county of Los Angeles, California, have invented a new, original, and ornamental Design for Hair Cutting Comb, of which the following is a specification, reference being had to the accompanying drawing, forming part thereof.

Fig. 1 is a perspective view of a hair cutting comb, showing my new design.

Fig. 2 is a plan view.

Fig. 3 is a top view.

Fig. 4 is an end view.

The salient features of my design are shown in full lines.

I claim:

The ornamental design for a hair cutting comb, substantially as shown and described.

SANFORD E. A. SANDERS.
